UNITED STATES PATENT OFFICE.

EBENEZER HILL, OF SOUTH NORWALK, CONNECTICUT.

CALCULATING INSTRUMENT.

1,145,020.

Specification of Letters Patent.

Patented July 6, 1915.

Application filed April 12, 1915. Serial No. 20,596.

To all whom it may concern:

Be it known that I, EBENEZER HILL, a citizen of the United States, residing at South Norwalk, in the county of Fairfield and 5 State of Connecticut, have invented a new and useful Improvement in Calculating Instruments, of which the following is a specification.

This invention relates to an instrument 10 which is designed for mechanically obtaining one of the factors employed in calculating the exact position of a body or locality on the earth, such for instance as the position of a ship at sea. One of the necessary 15 steps in solving such problems in navigation is to obtain the hour angle, that is, the distance in hours, minutes and seconds away from the meridian at a given time and at a given longitude of a selected star or 20 planet. This quantity is known in navigation as "t".

The object of this invention is to provide a very simple and compact instrument which can be easily and quickly manipulated 25 by any one familiar with navigating problems so as to give the desired hour angle or "t" without arithmetical calculation.

Figure 1 of the accompanying drawings shows a plan of the instrument. Fig. 2 30 shows a diametrical section of the same.

The instrument shown consists of five superposed disks made of any suitable material, as cardboard or celluloid, having different diameters and rotarily mounted with relation to 35 each other, with a wire or line which represents meridian extending radially across or visible from the front of the disks from the common axis of the disks to the periphery of the largest or bottom disk. The top or 40 smallest disk 1 is termed the "longitude" disk, and it is divided about its perimeter in each direction from zero marked "G" which stands for "Greenwich," into 180 degrees and fractions thereof, one side representing west longitude and the other side 45 east longitude, and the disk being so lettered. The second disk 2, which is somewhat larger than the first is termed the "sun" disk, or the "Greenwich mean time" 50 disk. Around the exposed portion of the perimeter this disk from zero, represented by the arbitrary symbol of the sun, is divided by graduations into hours and minutes from 1 to 12 on the first half and then 55 continuing from 1 to 12 on the second half,

these graduations representing the morning and afternoon hours of a day. The hour graduations on the sun disk register with the degree graduations on the longitude disk. The third or middle disk 3 is 60 termed the "Aries" disk or the "right ascension" disk. This disk is somewhat larger than the second disk and its exposed perimeter is graduated from zero, represented by the symbol of Aries—the sign of the 65 zodiac—into hours and minutes from 1 to 24. The 1 to 24 hour graduations on the Aries disk register with the 1 to 12 hour graduations on the sun disk.

The fourth disk 4, which is larger than 70 the third disk, is termed the "star" disk, and from zero represented by a star, the exposed perimeter of the disk is marked in hours and minutes from 1 to 24 in a reverse direction to that in which the hours 75 are marked on the Aries disk. The fifth or bottom disk 5, which is the largest, is the "time" disk or the "hour angle" disk. This is marked about its exposed periphery from the meridian line or zero in hours from 1 to 80 12 in each direction. The meridian line is desirably formed by the wire 6 which extends from the common axis of the disks, which may be held together by a portion of the meridian wire, to the zero point of the 85 largest or time disk, so that all of the disks except the bottom are capable of being rotated independently or together in both directions with relation to the meridian line 90 and the time disk.

This device is used in connection with the dead reckoning position of a ship and with the known factors taken from the *Nautical Almanac*, and the various disks are moved with relation to each other and in combination with each other to obtain the final result, which is read on the bottom or time disk after the other disks have been properly turned.

The following example shows how a problem can be solved by this instrument. Assume it is desired to find "t" or the hour angle of the star Spica on July 26, 1914, the Greenwich mean time taken from the chronometer being 12 h.—50'. In this problem 100 the dead reckoning position is taken to be 43°—23'—N and 67°—W. From the *Nautical Almanac* it is found that at this time the right ascension of this star is 13°—20' and the right ascension of mean sun is 8 h.—15', 110

In solving this problem, being in west longitude, the longitude disk is turned westward until the reading from "G" or Greenwich with relation to the hours on the sun disk is $12^{\circ} - 50'$. Both of these disks, that is, the longitude disk and the sun disk are then together rotated until the sun sign on the latter comes to 8 h.—15' on the Aries disk, this factor, 8 h.—15', being the right ascension of the mean sun at the hour and date as taken from the *Nautical Almanac*. These three disks, the longitude disk, the sun disk and the Aries disk are then together as one part rotated until the sign of Aries comes to 13 h.—20', the right ascension of the star taken from the *Nautical Almanac*, on the star disk. The four disks are then together rotated over the time disk until the meridian line is over the dead reckoning longitude, on the longitude disk, which is in the case assumed $67^{\circ} - W$. The star angle or "t" is then the distance between the meridian line and the star on the star disk, or as appears in the drawings is 3 h.—8', which is the answer to the problem assumed. This factor is then used by the usual method of calculation for obtaining the final result.

The instrument may be used for showing the value "t" in navigating problems without making the usual long arithmetical calculation. The device is also serviceable for graphically illustrating to students the method of making these calculations.

35 The invention claimed is;

1. A calculating instrument comprising a series of superposed, pivotally connected disks of different diameters, one disk having its perimeter provided with graduations representing 180 of each and 180 degrees of west longitude, one disk having its perimeter provided with graduations reading continuously representing twelve hours of morning and twelve hours of afternoon, one disk having its perimeter provided with graduations reading contra-clockwise representing twenty-four hours of a day, one disk having its perimeter provided with graduations reading clockwise representing twenty-four hours of a day, and one disk having its perimeter provided with graduations reading oppositely and representing twelve hourly periods in both directions from a zero at the meridianal line, and a meridian line extending radially with relation to said disks and

immovable with relation to the last mentioned disk.

2. A calculating instrument comprising a disk graduated into 360 degrees of longitude and reading in opposite directions from 0 to 180, a disk graduated into twenty-four hours and reading continuously from 0 to 12 and 0 to 12, a disk graduated into hours and reading from 0 to 24 contra-clockwise, a disk graduated into hours and reading from 0 to 24 clockwise, a disk graduated into twenty-four hours and reading in opposite directions from 0 to 12, and a meridian line immovable with relation to the last mentioned disk. 70

3. A calculating instrument comprising a series of superposed disks of different diameters pivotally mounted on a wire that extends radially from the common axis over the disks to the largest disks, one disk being graduated in degrees and reading in opposite directions from 0 to 180, one disk being graduated in hours and reading continuously from 0 to 12 and 0 to 12, one disk being graduated in hours and reading from 0 to 24 contra-clockwise, one disk being graduated in hours and reading from 0 to 24 clockwise, and one disk being graduated in hours and reading in opposite directions from 0 to 12. 75

4. A calculating instrument comprising a disk graduated with degrees of longitude, a disk graduated with the hours of morning and afternoon reading continuously, a disk graduated with the hours of the day reading contra-clockwise, a disk graduated with the hours of the day reading clockwise, a disk graduated with the hourly periods in opposite directions from a meridianal line, and a meridian line fixed with relation to the last mentioned disk. 90

5. A calculating instrument comprising a series of superposed disks of different diameters, a wire pivotally connecting said disks at the common axis thereof, said wire extending to and having its outer end fixed to the largest disk whereby all of the disks are rotatable with relation to the largest disk and the wire on which they are pivoted, said disks having their exposed perimeters graduated respectively with degrees of longitude, hours of morning and afternoon, and hours of the day, substantially as specified. 100 105
